UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,163,761.

Specification of Letters Patent. Patented Dec. 14, 1915.

Application filed June 11, 1913. Serial No. 772,966.

To all whom it may concern:

Be it known that I, ALFRED G. F. KUROWSKI, a citizen of the United States, residing in Brooklyn borough, in the county of Kings, city and State of New York, have invented certain new and useful Improvements in Type-Writing Machines, of which the following is a specification.

My invention relates to power apparatus for operating the line-space mechanism and returning the carriage at the completion of each typewritten line.

An object of the invention is to provide an improved form of driving connections, comprising a rack and pinion, between the motor, the carriage, and the line-space mechanism.

A further feature of the invention is to provide an improved means for automatically cutting off the power and disconnecting the motor before the carriage has completed its return movement, the point of cut-off being automatically varied to correspond with the distance through which the carriage is returned.

The invention further provides means for regulating the point of cut-off to correspond with the adjustment of the margin-stop which controls the left-hand margin of the work-sheet.

An electric motor is geared to a drive shaft having a pinion meshing with a rack on the carriage frame. Said rack through suitable connections operates a cam to actuate the line-spacer, the rack having a limited longitudinal movement relative to the carriage to permit such operation, the rack and carriage then being movable together as a unit to return the carriage preparatory to writing a new line.

The motor circuit is closed by means of a key lever which moves a frame carrying a movable switch contact into engagement with a stationary contact. Said frame also operates a clutch to connect the motor with the driving shaft. As the carriage approaches the limit of its return movement, said frame is automatically released to open the clutch and the electric switch, by means of an actuator consisting of a depending finger carried by a nut which is threaded on the drive shaft and travels downward during the return of the carriage. Said finger operates through an interponent member and an adjustable wedge to actuate

a trip for releasing the switch frame. The interponent member is moved along the wedge during the letter-feed travel of the carriage, and thereby automatically set to cut off the power at a point in the carriage 60 return varying with the distance the carriage has traveled forward.

The wedge is also adjustable to vary the point of cut-off, being connected to an indicator which may be set to correspond with 65 the position of the margin-stop controlling the left-hand margin of the work-sheet.

Other features and advantages will hereinafter appear.

In the accompanying drawings, Figure 1 70 is a perspective rear view of an Underwood typewriting machine with my invention applied thereto. Fig. 2 is a top plan view showing the power-operated means for operating the line-space mechanism. Fig. 3 is 75 a part sectional front elevation view of the invention, the parts being in the position assumed as the carriage nears the end of a line in its forward movement, and the indicator being set at an intermediate position. 80

Fig. 4 is a view showing the relation of the parts shown in Fig. 3, as the carriage nears the end of its return movement, but before the trip has operated to open the motor circuit. Fig. 5 shows the parts as viewed from 85

the right-hand side of Fig. 4. Fig. 6 shows the position of the parts when the carriage is at the end of its forward movement and after the switch has been closed, the margin indicator being set at zero. Fig. 7 is a 90 similar view, but with the indicator shifted to its extreme position in the other direction. Fig. 8 shows the relation of parts as the carriage nears the end of its return movement and is in the act of operating 95 the trip to open the switch. Fig. 9 shows the position of the parts when the carriage is at an intermediate position in its forward travel.

The carriage 1 is mounted to travel horizontally on front and rear guide rails, including a rear guide rail 2 secured to the frame 3 of the typewriting machine. A rotary platen 4 is journaled in a platen frame 5 connected to a rock shaft 6 on the carriage frame, whereby the platen may be shifted to upper and lower-case positions. A line-space wheel 7 fixed to the platen axle 8 is rotated by a pawl 9 pivoted on a slide 10 operated by an arm 11 on the line-space 110

lever 12. A returning spring 13 is connected at its ends to said slide and the platen frame.

A spring-pressed detent 14 bearing against 5 the line-space wheel holds the platen in adjusted position. The carriage is driven in a forward direction by a spring barrel 15 connected through a band 16 to the carriage.

The forward or letter-feed movement of 10 the carriage is controlled by escapement mechanism comprising escapement dogs 17 coöperating with an escapement wheel 18 driven by a pinion 19 in mesh with a rack 20 on the carriage. The escapement dogs may 15 be actuated in the usual manner by a universal bar in the path of the type-bars.

The return movement of the carriage may be effected by an electric motor M mounted on a bed plate or frame 21 which may be 20 secured to the machine frame 3. On the motor shaft is a worm 22 running in mesh with a worm gear 23 carried by a clutch member 24 loosely mounted on a vertical drive shaft 25. Said shaft is journaled in 25 upper and lower arms 26 and 27 on a vertical standard 28 on the frame 21.

Fixed to the drive shaft 25 is a pinion 29 in mesh with a rack 30 parallel with the platen and having a limited sliding movement 30 in the direction of its length in a guide rail 31 fixed to the carriage frame. A rod 32, parallel with the rack 30 and supported in brackets 33 on the rail 31, extends loosely through an opening in a standard or post 34 rising from the rack. A link 35 connects the standard 34 with an arm 36 which rocks on a shaft 37 and carries a cam 38. The cam engages an anti-friction roller 39 on a sliding bar 40 to which is secured a depending plate or lug 41 in front of a pin 42 on the slide 10. It will be seen that, through the connections just described, a longitudinal movement of the rack 30 in the guide rail 31 will actuate the cam 38 and thereby 45 move the slide bar 40 rearwardly, carrying with it the line-space pawl and slide to rotate the platen. The line-space mechanism, however, may be operated independently of the power mechanism if desired, the slide 50 bar 40 remaining stationary when the lever 12 is operated. A collar 43 adjustable on the rod 32 forms an adjustable stop to limit the return movement of the cam. When the rack 30 is driven by the electric motor, it 55 moves first in the guide rail 31 to actuate the line-space mechanism as above described, and then the rack and carriage are moved together as a unit to return the carriage. When the motor is disconnected from the 60 rack, the line-space mechanism and the rack are restored to initial position by a spring 44.

The circuit for the electric motor M is established by closing a switch comprising a stationary contact 45 mounted on a base 46 and a movable contact 47 in the form of a 65

resilient arm on a block 48 carried by but insulated from a switch frame 49. Said frame comprises upwardly extending arms 50 and 51 on opposite sides of the standard 28, the arms being pivoted at their upper 70 ends to one end of a clutch lever 52, the opposite end of which is pivoted at 53 to a bracket arm 54 on the standard 28.

The switch and the clutch are operated by a carriage return key 55 on a lever 56 75 pivoted at 57 and having its rear end extending beneath an arm 58 having a pivot 59. The free end of the arm 58 extends beneath the switch frame 49. When the key 55 is depressed, the arm 58 lifts the switch frame and brings the switch contact 47 into engagement with the contact 45. The upward movement of the switch frame 49 is opposed by a spring 60 (Fig. 4) which also tends to swing said frame about its pivot 61, 80 but such swinging movement is controlled by a bracket 62 having a vertically disposed face against which bears a pin 63 on the arm 50 of the frame. As said frame is thus lifted, and after the switch contacts have 85 been brought together, the frame is snapped forward as the pin 63 is permitted to enter a notch 64 in the bracket 62, said notch forming a ledge to support the pin, and with it the frame, in operated position. 95

The clutch comprises the upper member 24 already referred to, which carries the worm gear 23, and is loosely mounted on the drive shaft 25 and held against vertical movement by the bracket 54. A lower clutch 100 member 65 is vertically movable on the shaft into and out of clutching engagement with the member 24, but is prevented from rotating independently of the shaft by a key 66 working in a groove 67 in the shaft. The 105 clutch members 24 and 65 are respectively provided with clutch teeth 68 and 69, the latter being yieldingly mounted, as shown in Fig. 3. The lower clutch member is lifted by the clutch lever 52 to operative position 110 when the frame 49 is lifted, and thereby establishes a driving connection between the motor M and the drive shaft 25. 115

The lower end of the shaft 25 is threaded to receive a nut 70 which is prevented from 120 rotating with the shaft and thereby caused to travel up and down on the shaft during the forward and return movement of the carriage. A depending finger 71 adjustable in the nut 70 operates through interponent members 72 and 73 to actuate a trip lever 74, and thereby trip the frame 49 to open the switch and the clutch. The trip lever 74 is in the form of a bell crank pivoted at 75, and having an arm extending upward behind a pin 76 on the arm 51 of the switch frame 49. The other arm of the bell crank carries a pin 77 on which rests the interponent member 73, which is in the form of a cam or wedge on the end of a horizontal arm 125 130

78. The interponent 72 is pivoted to a depending arm 79 connected by a pivot 80 in the standard 28 and having a cam projection 81 entering a notch in the nut 70 and 5 having its cam surface bearing against the nut.

During the forward or letter-feed movement of the carriage the shaft 25 rotates in a direction to move the nut 70 upwardly, 10 and as the nut rides along the cam 81 the interponent 72 is carried inward a distance corresponding to the travel of the carriage. As the interponent moves upward along the cam 73, the point at which the cut-off takes 15 place in the return movement of the carriage is gradually changed. If, for example, a complete line is written, the interponent 72 is elevated sufficiently to effect the cut-off of the power at a comparatively early point in 20 the return travel of the carriage so that the momentum of the carriage will be substantially overcome by the opposing motor 15 before the carriage is brought to the limit of its travel, and an easy stop thereby is 25 effected. If the carriage is returned from an intermediate position, the position of the interponent will be such as to cause a cut-off at a later period corresponding to the shorter distance required in which to slow 30 down the carriage owing to the smaller momentum acquired during the comparatively short return movement. The finger 71 which forms an actuator for operating the trip is adjustable up and down in the nut to 35 vary the point of cut-off to correspond with the power of the electric motor or other factors determining the proper point of cut-off.

During the return movement of the carriage the arm 79 is held stationary by a friction 40 device, as shown in Fig. 5, comprising a pivoted arm 82 carrying a bow spring 83 between the arm 82 and the interponent 72. While the carriage is returning, the switch frame 49 is in its elevated position, as 45 shown in Fig. 5, and the arm 51 holds the arm 82 in position to compress the spring 83 and apply pressure to the interponent 72 to hold it in adjusted position. When the power is cut off, and the switch frame 49 falls, a cam recess 84 in the arm 51 permits the spring 83 to swing free of the interponent. The holding pressure on the latter being removed, it is free to be returned to its starting position by a spring 85.

55 The point at which the carriage is stopped at the end of its return movement is controlled by a carriage stop 86 adjustable along the scale 87 on the machine frame, this stop determining the width of the left-hand margin of the work-sheet.

In order to vary the point of cut-off for the motor M to correspond to the adjustment of the carriage stop 86, the wedge 73 is made adjustable, the arm 78 carrying said wedge 60 being connected to a rock arm 88 on a rock

shaft 89 to the forward end of which is fixed an arm 90 connected through a link 91 to a disk 92 pivoted to a dial plate 93. The latter is provided on its front face with scale markings or numbers over which travels a pointer 94 on the disk 92, adjustable by means of a button 92a on the disk, said numbers corresponding to the markings on the scale 87. When the pointer 94 is moved to the right from the zero position (Fig. 6), 70 the wedge 73 is carried to the left, as indicated in Fig. 7, and thereby positioned to effect an earlier cut-off of the motor. The pointer 94 is set to correspond with the position of the pointer on the stop 86. Thus, as 75 shown in Fig. 3, the stop 86 is at "20" on the scale and the pointer 94 is also at "20" on the dial, the mechanism for adjusting the wedge 73 being proportioned to vary the point of cut-off to correspond with the adjustment of the carriage stop. 80

It will be noted that three different means are provided for regulating the point of cut-off for the motor M; first, the actuator 71, which is adjustable to suit the strength of the motor, weight of the carriage, etc.; second, the interponent 72 is automatically adjusted during the travel of the carriage to correspond with the length of line written; third, the wedge 73 is adjustable to correspond with the position of the carriage stop. 90 As these several adjustments do not interfere in any way with each other, provision is made for effecting the proper slowing down of the carriage through widely varying conditions. 95

The operation may be briefly summarized as follows: The carriage stop 86 is set to secure the desired left-hand margin on the work-sheet and the pointer 94 correspondingly adjusted on the dial. As the carriage travels forward during the writing of a line, the shaft 25 is rotated by the rack 30 on the carriage, but as the clutch is open; no motion is imparted to the electric motor. During this forward movement the nut 70 travels upward and cams the interponent 72 a corresponding distance to the right. When a line or part of a line has been written and it is desired to return the carriage to starting position, the operator depresses the key 55, and thereby lifts the switch frame 49, closing the switch and bringing the clutch members together. The upward movement 110 of the switch frame also cams the arm 82 to the left (Fig. 5) and frictionally holds the interponent 72 stationary. The motor circuit being thus established and the clutch operated, the motor starts and drives the rack 30, operating the line-space mechanism, 115 and then drives the rack and carriage as a unit toward starting position. During this return movement the actuator 71 on the nut descends until it engages the interponent 72 and depresses the latter and the wedge 73, 120

125 In order to vary the point of cut-off for the motor M to correspond to the adjustment of the carriage stop 86, the wedge 73 is made adjustable, the arm 78 carrying said wedge 65 being connected to a rock arm 88 on a rock

operating the trip 74 and releasing the switch frame from the bracket 62. The current being cut off from the electric motor and the clutch opened, the carriage is gradually slowed down by the motor 15. The interponent 72 being released from the spring 83 as the switch frame drops, is immediately thrown to starting position.

Although the invention is herein shown as 10 adapted and applied to an Underwood typewriting machine, it will be understood that the principles involved may be applied to various other makes of machines.

Variations may be resorted to within the 15 scope of the invention, and portions of the improvements may be used without others.

Having thus described my invention, I claim:

1. In a typewriting machine, the combination 20 with a carriage, a rotatable platen thereon and line-space mechanism, of a rack extending in the direction of the carriage travel and having a limited movement relative to the carriage, means operated by the 25 rack during said limited movement to operate the line-space mechanism, a motor to drive the rack and carriage in one direction, a clutch between said motor and carriage, means to automatically operate the 30 clutch to release the carriage from the motor, and means operated by the carriage to automatically vary the time at which the clutch is operated.

2. In a typewriting machine, the combination 35 with a carriage having a letter-feed travel, a rotatable platen thereon and line-space mechanism, of a rack extending in the direction of the carriage travel and having a limited movement relative to the carriage, 40 means operated by the rack during said limited movement to operate the line-space mechanism, a power device to drive said rack and thereby operate the line-space mechanism and return the carriage, means 45 to automatically disconnect the carriage from the power device during the return of the carriage, and means operated by the rack during the letter-feed travel of the carriage to automatically determine the period at 50 which the carriage is disconnected.

3. In a typewriting machine, the combination 55 with a carriage, a rotatable platen and line-space mechanism, of a rack on the carriage, means connected thereto to operate the line-space mechanism, a pinion in mesh with said rack, a motor, gearing between the motor and said pinion comprising a clutch, a trip operated by the carriage to open the clutch, and an interponent between the trip 60 and carriage and operated by the carriage to automatically vary the period in the travel of the carriage at which the trip is operated.

4. In a typewriting machine, the combination 65 with a carriage, a rotatable platen and line-space mechanism, of a member slidably

mounted on the carriage for movement longitudinally thereof, connections between said member and line-space mechanism for actuating the latter, means to drive said member to operate the line-space mechanism 70 and then return the carriage, means to disconnect said slideable member from the driving means when the carriage is at an intermediate point during its return travel, a stop adjustable to variably limit the return 75 movement of the carriage, and means to vary the said point of disconnection to correspond with the adjustment of the stop.

5. In a typewriting machine, the combination 80 with a carriage, a platen and a line-space mechanism, of a slide movable transversely of the platen to operate said mechanism, a cam to operate said slide, a rack bar extending longitudinally of the carriage, a connection between the rack bar and said 85 cam, a motor for moving the rack bar on the carriage to operate the line-space mechanism and then moving the rack bar and carriage as a unit, an adjustable stop for the carriage, means to automatically disconnect 90 the motor from the carriage as the latter approaches the limit of its travel determined by said stop, and means to adjust said point of disconnection to correspond with the adjustment of said stop. 95

6. The combination with a carriage, a rotatable platen and line-space mechanism, 100 of a rack on the carriage, means connecting the rack to the line-space mechanism, a motor, gearing comprising a clutch between the 105 motor and the rack to drive the latter and thereby first operate the line-space mechanism, and then drive the rack and carriage as a unit to return the carriage, a trip to release the motor from the rack during the 110 return of the carriage, and an interponent between the carriage and trip and adjusted by the forward travel of the carriage to vary the point at which the trip is operated to correspond to the distance through which 115 the carriage is returned.

7. In a typewriting machine, the combination 115 with a carriage, a motor to drive it forward, and a second motor to return the carriage, of a drive shaft geared to said second motor, a rack and pinion between said drive shaft and the carriage, means operated by said drive shaft to automatically cut off the power during the return travel of the carriage, and means to automatically vary 120 the point of cut off to correspond with the distance through which the carriage is returned.

8. The combination with a carriage and 125 a motor to return the carriage, of a drive shaft, a driving connection between said shaft and the carriage, gearing between said shaft and motor comprising a clutch, a trip device to hold the clutch in operative position and a nut traversed by said shaft to ac- 130

tuate said trip device and open said clutch during the return movement of the carriage.

9. The combination with a carriage and a motor to return the carriage, of a drive shaft, a driving connection between said shaft and the carriage by which the shaft is positively driven when the carriage is moved in either direction independently of the motor, gearing between said shaft and 10 motor comprising a clutch, and means operated by said shaft to open said clutch during the return movement of the carriage at a point automatically variable to correspond with the distance through which the carriage 15 is returned.

10. In a typewriting machine, the combination with a carriage and a motor to return the carriage, of a drive shaft geared to the carriage, gearing between the drive 20 shaft and motor comprising a clutch, a manual device to operate the clutch and establish a driving connection from the motor to the carriage, a trip to release the clutch, and an actuating device operated by the 25 drive shaft to operate the trip and disconnect the clutch members during the return travel of the carriage, the drive shaft being rotatable by the carriage when the latter is operated in either direction, whereby the 30 position of said actuating device relative to the drive shaft is determined and controlled by the position of the carriage.

11. In a typewriting machine, the combination with a carriage and a motor to return 35 the carriage, of a drive shaft geared to the carriage and rotatable by the carriage in both directions, gearing between the drive shaft and motor comprising a clutch, a manual device to operate the clutch and establish a driving connection from the motor to the carriage, a trip to release the clutch, and an actuating device operated by the 40 drive shaft to operate the trip and disconnect the clutch members during the return 45 travel of the carriage at a point automatically variable to correspond with the position of the carriage at the moment the clutch is released.

12. In a typewriting machine, the combination with a carriage and a motor to return 50 the carriage, of a drive shaft geared to the carriage, gearing between the motor and drive shaft comprising a clutch, a key connected to operate the clutch and thereby 55 connect the motor to drive the carriage, means to hold the clutch in operated position, a trip to release the clutch, an actuating device driven by said shaft, and an interponent between said actuating device and 60 the trip for operating the latter, said interponent being adjustable to effect the operation of the trip at different points in the travel of the carriage.

13. In a typewriting machine, the combination with a carriage and a motor to return 65

the carriage, of a drive shaft geared to the carriage, gearing between the motor and drive shaft comprising a clutch, a key connected to operate the clutch and thereby connect the motor to drive the carriage, 70 means to hold the clutch in operated position, a trip to release the clutch, an actuating device driven by said shaft, an interponent between said actuating device and the trip for operating the latter, and means 75 to automatically shift the interponent during the forward travel of the carriage, and thereby vary the point at which the trip is actuated to correspond with the distance through which the carriage is returned. 80

14. In a typewriting machine, the combination with a carriage and a motor to return the carriage, of a drive shaft having a rack and pinion connection with the carriage, gearing between the motor and said shaft 85 comprising a clutch, a key to operate said clutch and connect the motor to the drive shaft, means to hold the clutch in operated position, a trip to release the clutch, a traveling nut threaded on the drive shaft for 90 operating the trip, an interponent between said nut and the trip, and means to cause a movement of the interponent throughout the forward travel of the carriage so that the trip will be actuated when the carriage 95 has reached a point in its return movement automatically varied to correspond with the position of the carriage at the time the clutch is operated.

15. In a typewriting machine, the combination with a carriage and a motor to return the carriage, of a drive shaft geared to the carriage, gearing between the motor and said shaft comprising a clutch, a key to operate the clutch and connect the motor 100 to the drive shaft, means to hold the clutch in operated position, a trip to release the clutch, a traveling nut on said shaft, an interponent, a cam between said nut and the trip, and a second cam operated by said nut 105 to cause the interponent to travel along said first-named cam during the forward travel of the carriage, and thereby vary the point at which the trip will be actuated during the return movement of the carriage. 115

16. In a typewriting machine, the combination with a carriage, a motor and connections from the motor to the carriage for returning the latter, of a device to cause the power of the return drive to be cut off after 120 the carriage has traveled part way to the starting point, said device having a variable adjustment or movement automatically proportioned in each instance to the extent of letter-feed forward movement of the carriage, whereby the device is set to cause the power to be cut off when the carriage is a greater or less distance from the limit of its return movement in accordance with the length of the line from which the return is 125 130

made, an adjustable carriage stop, and means coöperating with said cut-off device to additionally vary the point of cut-off to correspond with the position of the carriage stop.

17. In a typewriting machine, the combination with a carriage, a motor and connections from the motor to the carriage for returning the latter, of means to cut off the power after the carriage has traveled part way to the starting point, means to vary the time of such power cut-off for successive lines so that the distance of the carriage from the starting point is automatically varied in accordance with the length of the line from which the return is made, an adjustable carriage stop determining said starting point, and mechanism for additionally varying the time of the power cut-off to correspond with the position of the carriage stop.

18. In a typewriting machine, the combination with a carriage and power-operated return mechanism therefor, of means to cut off the power when the carriage is at a point automatically variable with the length of line from which the carriage is returned and variable with the position to which the carriage is returned.

19. In a typewriting machine, the combination with a carriage and a power-operated return mechanism therefor, of means to cut off the power when the carriage is at a point automatically variable with the position from which the carriage is returned, an adjustable carriage return stop, and a device settable to correspond with said return stop and thereby additionally vary the point at which the power is cut off to correspond with the position of the return stop.

20. In a typewriting machine, the combination with a carriage and power-operated return mechanism therefor, of a carriage return stop, means to effect a slowing down of the carriage through a range of its return movement automatically variable with variations in the acceleration of the carriage, and additional means to control said range of movement to compensate for adjustment of said stop.

21. In a typewriting machine, the combination with a carriage, a power device to return the carriage, an adjustable stop to limit the return movement of the carriage, and a scale to indicate the position of said stop, of means to automatically cut off the power during the return movement, a device adjustable in conjunction with said stop to vary the point of cut-off to correspond with the position of said stop, and an indicator to indicate adjustment of said device corresponding to the adjustments of the said stop.

22. In a typewriting machine, the combination with a carriage, of a power device to

return the carriage, a carriage stop, a scale to indicate the position of said stop, means to cut off the power during the return movement of the carriage, a device adjustable to vary the point at which the power is cut off during the return of the carriage, a second scale, a pointer movable over said scale, and operating connections between said pointer and said adjustable device.

23. In a typewriting machine, the combination with a carriage, a power device to return the carriage and means to cut off the power during the return travel of the carriage, of scales, pointers working over said scales, a carriage stop connected with one pointer, and a device connected with the other pointer to vary the point of power cut-off to correspond with the position of the carriage stop, whereby when the pointers are adjusted to corresponding positions on the scales, the slowing down of the carriage will take place through approximately the same length of travel of the carriage for any adjustment of the pointers.

24. In a typewriting machine, the combination with a carriage, a power device to return the carriage and means to automatically cut off the power during the return travel of the carriage, of a device adjustable to vary the point at which the power is cut off, and an indicator operatively connected to said device.

25. In a typewriting machine, the combination with a carriage and a motor to return the carriage, of an element having a positive driving connection with the carriage enabling the carriage to drive said element in either direction, gearing comprising a clutch between the motor and said element, a device to automatically open said clutch during the return travel of the carriage, and means driven by said element to automatically vary the point at which the clutch is opened to correspond with the position from which the carriage is returned.

26. In a typewriting machine, the combination with a carriage and a motor to return the carriage, of a shaft having a permanent driving connection with the carriage, enabling the carriage to drive said shaft in either direction, a clutch between the motor and said shaft, means to open the clutch during the return travel of the carriage, and a device actuated by said shaft to vary the point in the carriage travel at which the clutch is opened to correspond with the distance through which the carriage is returned.

27. In a typewriting machine, the combination with a carriage and a power device to drive the carriage, of means to automatically cut off the power from the carriage before the carriage has completed its movement, said cut-off means comprising a device adjustable to cause the power to be cut off

when the carriage is at a point variable with the adjustment of said device, and an indicator connected to said adjustable device and movable therewith.

5 28. In a typewriting machine, the combination with a carriage and a power device to drive the carriage, of means to automatically cut off the power from the carriage before the carriage has completed its movement, said cut-off means comprising a device adjustable to cause the power to be cut off when the carriage is at a point variable with the adjustment of said device, an indicator connected to said device, and an 10 adjustable stop to limit the travel of the carriage, said indicator comprising a graduated scale to enable said cut-off device to be set to correspond with the adjustment of the carriage stop.

20 29. In a typewriting machine, the combination with a carriage, of a motor to drive the carriage, an adjustable stop to limit the travel of the carriage, means to automatically cut off the driving power of the motor from the carriage before the latter has reached said stop, whereby the carriage may be slowed down before it reaches the stop, said cut-off means comprising a device adjustable to vary the time at which the power 25 is cut off, and an indicator connected to said device and adjustable therewith, said indicator comprising a pointer movable over a scale, graduated to enable the adjustable device to be set to correspond with the adjustment of the carriage stop.

30 30. In a typewriting machine, the combination with a carriage, a carriage stop and a graduated scale to indicate the position at which the stop is set, of a motor to drive the carriage, means to automatically cut off the driving power of the motor from the carriage before the carriage reaches said stop, said cut-off means comprising a device 40 adjustable to vary the time of cut-off to correspond with the adjustment of the carriage stop, and an indicator connected to said adjustable device for movement when said device is moved, said indicator comprising a pointer and a graduated scale over which 45 the pointer moves, which pointer when set at the scale graduation corresponding to the setting of the carriage stop along its scale causes the power to be cut off when the carriage is at a predetermined distance 50 from the stop, said distance being substantially the same for all adjustments of the carriage stop when the said pointer is set to correspond with the position of the carriage stop.

60 31. In a typewriting machine, the combination with a carriage and a motor to drive the carriage, of a device to cut off the driving power of the motor from the carriage during the travel of the carriage, an adjustable device adjustable to cause the power to

be cut off while the carriage is in a position determined by the adjustment of said adjusting device, indicating means comprising a scale with numbered graduations, and a pointer moving over the scale, said pointer 70 connected to said adjusting device for operating the latter and shifting the point of cut-off through a number of letter-spaces corresponding to the difference between the numbers from one to the other of which said pointer has been moved over the scale.

32. In a typewriting machine, the combination with a carriage and a motor for returning the carriage after each line of writing, of a key operable to cause the motor to return the carriage, a device for automatically cutting off the driving power from the carriage before the carriage has completed its return travel, an adjusting device operated during the forward or letter-feed 80 travel of the carriage to a position determined by the length of the line written, said adjusting device operable to vary the point at which the power is cut off to correspond with the length of the line from which the carriage is returned, whereby the carriage is slowed down after the power is cut off through a distance varying with the length of line from which the carriage has been returned, an adjustable stop to limit the 85 return movement of the carriage, and a manually adjustable device coöperating with said first-named adjusting device and settable to vary the point of cut-off to correspond with the adjustment of said stop.

33. In a typewriting machine, the combination with a carriage and a motor for returning the carriage after each line of writing, of a key operable to cause the motor to return the carriage, a device for automatically cutting off the driving power from the carriage before the carriage has completed its return travel, an adjusting device operated during the forward or letter-feed travel of the carriage to a position determined by 100 the length of the line written, said adjusting device operable to vary the point at which the power is cut off to correspond with the length of the line from which the carriage is returned, whereby the carriage is slowed down after the power is cut off through a distance varying with the length of the line from which the carriage has been returned, an adjustable stop to limit the return movement 105 of the carriage, a manually adjustable device coöperating with said first-named adjusting device and settable to vary the point of cut-off to correspond with the adjustment of said stop, and an additional adjusting device to further vary the point at which the power is cut off.

34. In a typewriting machine, the combination with a carriage and a motor for driving the carriage of a clutch between the motor and carriage, a key to operate said clutch

for effecting a driving connection between the motor and carriage, a trip to release said clutch and thereby disconnect the motor from the carriage during the travel of the carriage, a trip-operating device geared to the carriage for movement in unison therewith, a series of interponents between said operating device and the trip, each adjustable independently of the other to vary the point at which, during the travel of the carriage, the trip is operated, means automatically operated during the forward travel of the carriage to shift one of said interponents to a position determined by the length of the line written, to thereby automatically vary the point of cut-off to correspond with the length of line from which the carriage is returned, an adjustable stop to limit the return movement of the carriage, and a manual device to adjust another of said interponents to correspond with the adjustment of said stop, and another of said interponents also manually adjustable to further vary the point of cut-off.

35. In a typewriting machine, the combination with a carriage and a motor to return the carriage, of a shaft, gearing comprising a clutch between said shaft and the motor for causing the motor to rotate said shaft, gearing between the shaft and carriage through which the motion of said shaft is transmitted to the carriage to return the carriage, and through which the carriage is operative to drive said shaft during the forward travel of the carriage, a nut threaded on said shaft to travel therealong as the shaft rotates, and means operated by said nut to open the clutch during the return travel of the carriage.

36. In a typewriting machine, the combination with a carriage and a motor to return the carriage, of a shaft, gearing comprising a clutch between said shaft and the motor for causing the motor to rotate said shaft, gearing between the shaft and carriage through which the motion of said shaft is transmitted to the carriage to return the carriage, and through which the carriage is operative to drive said shaft during the forward travel of the carriage, a nut threaded on said shaft to travel therealong as the shaft rotates, means operated by said nut to open the clutch during the return travel of the carriage, and a device also operated by said nut to automatically vary the point in the carriage travel at which the clutch is opened in accordance with variations in the position from which the carriage is returned.

37. In a typewriting machine, the combination with a carriage and an electric motor to return the carriage, of a drive shaft, gearing comprising a clutch between the drive shaft and the motor for causing the

motor to rotate said shaft, gearing between the shaft and carriage through which the motion of said shaft is transmitted to the carriage to return the carriage, and through which the carriage is operative to drive said shaft during the forward travel of the carriage, a switch controlling the supply of current to the motor, a switch frame connected to the switch and clutch, a key for operating said frame to close the switch and clutch, a device to hold said frame in operated position, a trip to release said frame, and a device driven by said shaft for operating the trip during the return travel of the carriage.

38. In a typewriting machine, the combination with a carriage and an electric motor to return the carriage, of a drive shaft, gearing comprising a clutch between the drive shaft and the motor for causing the motor to rotate said shaft, gearing between the shaft and carriage through which the motion of said shaft is transmitted to the carriage to return the carriage, and through which the carriage is operative to drive said shaft during the forward travel of the carriage, a switch controlling the supply of current to the motor, a switch frame connected to the switch and clutch, a key for operating said frame to close the switch and clutch, a device to hold said frame in operated position, a trip to release said frame, a device driven by said shaft for operating the trip during the return travel of the carriage, and an interponent between said device and the trip automatically operated during the forward travel of the carriage, and controlling the point at which the trip is operated during the return of the carriage.

39. In a typewriting machine, the combination with a carriage, of an electric motor, gearing between the motor and carriage to return the carriage, said gearing comprising a clutch, a clutch-operating device, a switch in the motor circuit, a key for closing said switch and operating said device to connect the motor with the carriage, means to hold the clutch-operating device and the switch in operated position independently of the key, a trip to release said device and open said switch, a trip-operating device geared to the carriage for automatically actuating said trip and opening said switch, thereby disconnecting the carriage from the motor and opening the motor circuit before the carriage has completed its return movement, means automatically adjusted during the forward travel of the carriage to positions corresponding to the length of the forward travel of the carriage to thereby automatically vary the time at which, during the return of the carriage, the trip is actuated, an adjustable carriage stop to limit the return movement of the carriage, and manually adjustable means to vary the point at

which the trip is actuated to correspond with the adjustment of said carriage stop.

40. The combination with a typewriter carriage and a motor to return the carriage, of means to automatically cut off the power before the carriage has completed its return movement, said means comprising a device to control the point of cut-off, and an actuator to set said controlling device, said actuator having a connection with the carriage whereby it is moved by the carriage during the forward travel of the latter, to a position determined by the extent of said forward travel, to correspondingly position said controlling device, and thereby automatically vary the point at which the power is cut off during the return of the carriage to correspond to the length of the line from which the carriage is returned, said connection of 20 the actuator with the carriage operative to cause the actuator to be restored by the carriage during the return of the carriage.

41. The combination with a typewriter carriage and a power device to return the carriage, of means to automatically cut off the power during the return of the carriage as it approaches its starting position, said means comprising an actuating device operatively connected to the carriage, and means 30 positioned thereby during the forward travel of the carriage to control and vary the point of cut-off during the return of the carriage to correspond with the length of the line from which the carriage is returned, the connection between the carriage and said actuating device being operative to restore the latter when the carriage is returned independently of the power device.

42. The combination with a typewriter carriage and a power device to return the carriage, of means to automatically cut off the power during the return of the carriage as it approaches its starting position, said means comprising an actuating device operatively connected to the carriage, means positioned thereby during the forward travel of the carriage to control and vary the point of cut-off during the return of the carriage to correspond with the length of the line 45 from which the carriage is returned, the connection between the carriage and said actuating device being operative to restore the latter when the carriage is returned independently of the power device, an adjustable carriage stop to limit the return movement of the carriage, and means for manually varying the point of cut-off to correspond with the adjustment of said stop.

43. The combination with a typewriter carriage and a motor to return the carriage, said motor disconnected from the carriage during the forward travel of the latter, of means for connecting the motor to the carriage to return the latter, means for disconnecting the motor from the carriage as the

latter approaches its initial position during the return of the carriage, said disconnecting means comprising a device to control the time at which the motor is disconnected, and an actuator for said device, said actuator 70 having a connection with the carriage, whereby it is driven to set said controlling device at a position corresponding to the length of the line from which the carriage is returned, and whereby the actuator may 75 be restored by the carriage during the return of the latter.

44. The combination with a typewriter carriage and a motor, of gearing between the motor and carriage comprising a clutch 80 open during the forward travel of the carriage and permitting the carriage to travel in either direction while the motor is at rest, means to operate said clutch to connect the motor with the carriage and cause the motor 85 to return the carriage, means to hold the clutch in operated position, a trip to release said holding means and cause the motor to be disconnected from the carriage, means to automatically actuate said trip during the 90 return of the carriage, said last-named means comprising a device to control the time at which, during the carriage return, the trip is actuated, and an actuator geared to the carriage and driven thereby during 95 the forward travel of the carriage, to position said controlling device for effecting the disconnection of the motor at a point automatically variable with the length of the line from which the carriage is returned, the 100 gearing between said actuator and carriage operative to effect the restoration of the actuator during return of the carriage either manually or by the motor.

45. In a typewriting machine, the combination with a carriage and a motor to return the carriage, of a gear train between the carriage and motor comprising a clutch, a key to operate said clutch and connect the motor to the carriage for returning the latter, means for holding the clutch in operated position independently of the key, means to automatically open the clutch during the return of the carriage, said clutch-opening means comprising a device to control the 105 time at which the clutch is released, and an actuator having a driving connection with the carriage and operative to set said controlling device during the forward travel of the carriage, to a position corresponding to the extent of said forward travel, whereby the point at which the motor is disconnected from the carriage is automatically varied to correspond with the length of the line from which the carriage is returned, the carriage 110 being manually returnable independently of the motor, and said connection between the carriage and actuator being operative to restore the latter during the return of the carriage either manually or by the motor. 115 120 125 130

46. The combination with a typewriter carriage and a motor, of a driving connection between the motor and carriage comprising a normally open clutch permitting the carriage to be advanced and returned while the motor remains at rest, means to operate the clutch for connecting the motor to the carriage to return the latter, means to open the clutch during the return of the carriage, and means to automatically vary the point at which the clutch is opened and the motor disconnected, to correspond to the length of the line from which the carriage is returned, said last-mentioned means comprising an actuating device having a connection with the carriage for moving said device during the forward travel of the carriage to a point corresponding to the extent of said forward travel, and whereby said actuating device is returned by the carriage as the latter is manually returned.
47. The combination with a typewriter carriage, a motor, and connections from the motor to the carriage for returning the latter, of means to cut off the power before the carriage has completed its return travel, means to vary the time of such power cut-off for successive lines so that the distance of the carriage from the starting point at the time of cut-off is automatically varied in accordance with the length of the line from which the return is made, an adjustable car-

riage stop to determine the starting position of the carriage, means settable to additionally vary the time of the power cut-off to correspond with the position of the carriage stop, and manually adjustable means to further vary the time of the power cut-off independently of the adjustment of the carriage stop or the length of line from which the carriage is returned.

48. In a typewriting machine, the combination with a carriage and power-operated means to return the carriage, of means to cut off the power when the carriage is at a point automatically variable with the position from which the carriage is returned to permit a gradual slowing down of the carriage, an adjustable carriage-return stop, a device settable to correspond with the position of the return stop to thereby additionally vary the point at which the power is cut off to correspond with the position of the return stop, and independently adjustable means to further vary the point at which the power is cut off to correspond with the length of carriage travel required after the power has been cut off, to effect said slowing down of the carriage.
